ATTORNEY

UNITED STATES PATENT OFFICE

CHARLES J. HARRINGTON, OF CLOUTIER, MONTANA.

PATENT.

1,198,532.

Specification of Letters-patent. Patented Sept. 19, 1916.

Application filed May 1, 1914. Serial No. 34,117.

To all whom it may concern:

Be it known that I, C. J. Harrington, a citizen of the United States, residing at Cascade, in the county of Chouteau, in the State of Montana, have invented certain new and useful Improvements in Wrenches, of which the following is a specification:

This invention relates to an improvement in wrenches of the type known as "breakable wrench" and is designed to provide a simple and efficient means whereby the jaws of the wrench may be quickly separated to any desired distance within the range of the wrench and after being so set to lock the jaws firmly and securely against movement.

The principal object of the invention is to provide a wrench of the kind described with a rotatable handle, preferably made in sections, having retaining means engaged at its ends and a movable jaw with a stem extending into said handle, said handle and stem having interlocking means for holding the movable jaw in a set position, said means being quickly unlocked by a part of the handle.

A further object of the invention is to provide in said a wrench having fixed and movable jaws a slotted stem interengaging with a stem on the movable jaw, said stem 12, slide longitudinally in the slot 13 of the movable jaw stem, said movable stem having a row of transverse teeth on one edge adapted to be engaged by corresponding teeth on the surface of one section of a handle 11, the handle when the movable jaw is held firmly against movement. To accomplish this object the feature of the tubular handle is provided as mounted about the jaw stem is flared and collars whereby a limited movement of the handle will disengage the teeth thereon from the teeth on the movable jaw and cause the movable jaw to be quickly set in any position desired.

With the above as the principal object in view and other objects to be set forth in the following description, the invention consists in the novel construction and arrangement of parts described, claimed, and illustrated in the accompanying drawing in which:

Figure 1 is an elevation of the wrench

complete, Fig. 2 is an elevation of the handle 13 in right angles to Fig. 1 with the handle 13 in an upright position and a portion of the jaws 14 and 15 shown broken away, Fig. 3 is a longitudinal sectional view on the line 3--3 of Fig. 1, Fig. 4 is a similar view on the line 4--4 of the same figure, Fig. 5 is a view of a portion of the handle 13 seen from the inner side showing the locking ribs thereon, and "a" is a plan view of the lower end of the handle 13 showing the locking ribs thereon, and "b" is a plan view of the lower end of the handle 13 showing the locking ribs on said end.

Referring to the drawing by numbers, 10 indicates the fixed jaw and 11 the movable jaw of a breakable wrench, integrally formed with the fixed jaw and projecting at right angles thereto from its inner face is a stem 12 that extends longitudinally through the handle 13. The stem 12 is slotted as at 14 throughout its entire length, thus dividing the stem 12 into two equal parts 15. Between the two parts 15 is a stem 16 that projects longitudinally from the handle 13 and is adapted to receive the movable jaw 11. The movable jaw 11 is provided with a slot 13 in its outer side, the two parts 15 of the stem 12 being received in the slot 13. The upper end of the stem 16 is received in the slot 13 of the movable jaw 11, the movable jaw 11 being shown in a set position in Fig. 3, and shown in an unlocked position in Fig. 4, and shown in a position in which the movable jaw 11 is held firmly against movement in Fig. 5. The lower end of the movable jaw 11 is provided with a flared portion 17, which is flared in the direction of the handle 13, having a transverse slot 18, the lower end of the handle 13 being received in the slot 18, the handle 13 being held firmly against the movable jaw 11 by being downwardly from the handle 13 by a collar 19. At the lower end of the handle 13 is a smaller collar 21, having a slot 20 and on its outer side is provided with a slot 22 in the center thereof that extends down the lower end of within the handle 13, the stem 12 and is held in place thereon by a screw or bolt 24 passing through the slot 20 and through the stem 12.

Surrounding the two stems 12 and 16 is the handle 13 of tubular formation and hav-

ing reduced ends 30 which fit within the flanges 20, 22 of the respective collars 19 and 21 thus providing bearings upon which the handle 13 may be rotated.

5 On the lower end of the stem 16 and on one edge thereof are formed a number of transverse ribs or teeth 25 that project laterally beyond each side of said stem as shown in Fig. 4. These ribs or teeth have their outer edges of arcuate shape and are adapted to engage and interlock with a series of coöperating ribs 26 on the inner side of the tubular handle 13. The ribs on the handle extend from end to end thereof 15 so that in whatever position the movable jaw 11 may be placed the ribs 26 may by rotating the handle into the proper position be made to engage with the teeth 25 on the stem 16 and lock the jaw against further 20 movement. The length of the teeth or ribs 25 and 26 is such that when in perfect engagement as in Fig. 4 it is only necessary to give the handle a quarter revolution to disengage said teeth and permit the jaw 11 to be moved. To indicate to the user of the wrench when such teeth are interlocked and when disengaged suitable marks 27, 28 are 25 made on the collar 19 at the proper angular distance apart and a further mark 29 is 30 made on the handle 13 that coöperates with said marks on the collar to indicate when the teeth are engaged and when disengaged. The marks 27, 28 on the collar are distinguished by the words "On" and "Off." Any 35 other words may be used however in place of these.

The operation of the wrench is readily understood from the above description. By turning the handle 13 until the mark 29 40 coincides with the mark designated by "Off," the teeth 26 will be disengaged from the teeth 25 and the jaw 11 may be moved to or from the fixed jaw for any desired distance. After setting the jaw 11, a reverse movement of the handle 13 until the mark 29 45 coincides with the mark 27 indicated by "On," will again cause the teeth 26 to engage the teeth 25 and lock the jaw 11 immovable.

50 I claim:

1. In a wrench having a fixed jaw and a movable jaw, the latter being formed with a rectangular slot on each side extending in line with its direction of movement, of a 55 stem on said fixed jaw comprising two parallel members spaced apart the upper rectangular portions of which are seated in the slots in said movable jaw to form guides for the same, the lower ends of said members 60 being semi-cylindrical, a stem on the movable jaw slidable within the space between the fixed stem members and having a plurality of teeth or ribs on one edge disposed at right angles to the length of said stem, a

two-part tubular handle mounted to rotate 65 about the ends of the semi-cylindrical portion of said stems and secured on said fixed stem against longitudinal movement, flanged collars fixed on said semi-cylindrical portions of said fixed stem to hold the handle 70 sections together and permit rotation of the handle, and teeth or ribs on the interior of said handle adapted to engage and disengage the teeth on the movable stem as said handle is partly rotated and lock said movable jaw against movement when the teeth 75 are engaged.

2. In a wrench having a fixed jaw and a movable jaw, a stem on said fixed jaw comprising two parallel members spaced apart 80 between which the movable jaw is adapted to slide and serving as a guide for said jaw, a stem on the movable jaw disposed between said fixed jaw members, a plurality of curved teeth or ribs on one edge of said 85 slideable stem and extending beyond the sides thereof, said teeth or ribs extending perpendicular to the direction of movement of said stem, a collar having a polygonal opening mounted on said fixed stem upon a similarly 90 shaped shoulder to prevent rotation, a second collar on the extreme end of said fixed stem and secured thereto by a pin, a sectional tubular handle surrounding the fixed and movable stems rotatable between and 95 held together by said collars, and teeth or ribs on the inner surface of one of said handle sections adapted to engage and disengage the teeth on the movable stem when the handle is partly rotated and lock said stem 100 against movement when the teeth are engaged.

3. In a wrench having a fixed jaw and a movable jaw, a stem projecting from said fixed jaw and divided longitudinally 105 throughout its length by a centrally disposed slot, guide ways in opposite sides of the movable jaw in which said divided stem is adapted to slide, a stem projecting from the movable jaw and slidable in the fixed 110 stem, teeth or ribs on one edge of said slideable stem at the lower end thereof, spaced circular collars having projecting and opposing flanges fixed against rotation on the slotted stem, a tubular handle mounted to 115 rotate in said flanged collars, and a series of teeth or ribs within said handle to engage and disengage the teeth on the movable stem as said handle is rotated.

4. In a wrench having a fixed jaw, and a 120 movable jaw formed with a guide slot on each side, a divided stem on said fixed jaw straddling the movable jaw and seated in said guide ways to guide the movable jaw, a 125 stem on said movable jaw slidable between the members of the divided stem, flanged collars spaced apart and mounted on the divided stem, a tubular handle formed of

longitudinal sections rotatably mounted between said collars, the flanges of which collars engage the ends of the handle sections and prevent them separating, a plurality of transverse teeth or ribs on the interior of one of the handle sections, and a plurality of similar teeth or ribs on the stem of the movable jaw to be engaged and disengaged

by the teeth on the handle upon partial rotation thereof. ¹⁰

In testimony whereof I affix my signature in presence of two witnesses.

CHARLES E. GARRETSON.
